APPARATUS FOR PRODUCING INDIVIDUAL
MASSES OF ICE

Balthazar H. T. Mulch, Westwood, N. J.

Application December 19, 1935, Serial No. 55,146

16 Claims. (Cl. 62—108.5)

My invention relates to automatic refrigerators, and more particularly to apparatus for producing individual masses of ice in such refrigerators, especially for use in hotels, homes, etc.

5 In the household refrigerators now in general use the cooling coil is generally so constructed as to provide a freezing compartment within which metal or rubber trays filled with water may be inserted for the production of ice cubes. 10 To obtain the individual cubes the trays must be placed under the faucet and water allowed to play thereover until the ice is loosened from the tray. This must be done even when trays of rubber are employed, in spite of the fact that ice 15 does not cling strongly to rubber, for when the trays have remained a long time in the freezing compartment, incrustations of ice are formed around the edges of the trays and operate to lock the ice cubes to the trays. It is thus frequently 20 quite difficult to separate the cubes from the trays, and, as is well known, much difficulty is often encountered in removing the trays from the freezing compartment due to the deposition of frost within the spaces between the tray and the 25 walls of the freezing compartment, such frost operating to weld the trays to the compartment. When this happens, resort is often had to a screw driver or similar implement which is inserted between the tray and the wall of the freezing compartment, a procedure which involves the 30 danger of breaking parts of the apparatus.

According to the present invention, it is proposed to provide an improved ice-freezing mechanism by the aid of which individual masses of 35 ice can be formed within the freezing compartment and discharged into an easily accessible hopper in a very simple and convenient manner. The mechanism may be power or hand-operated, and in the latter case a handle member may be 40 arranged so as to be conveniently engageable outside of the freezing compartment or even upon the outside of the refrigerator, in which case the necessity of opening the door of the refrigerator is avoided.

45 The present invention contemplates the provision of endless conveyor means provided with cup-shaped buckets of rubber or rubber-like material which pass through a tank of water wherein they become automatically filled, cups on opposite conveyors being brought into registry and forced into sealing engagement with the aid of an automatically produced partial vacuum. These water-filled, sealed double cups then pass through the refrigerating space where the water 50 is frozen. The conveyors then separate at the upper limit of their run and the frozen bodies of ice are then ejected into a trough, which terminates in a collecting hopper at the outside of the freezing compartment or of the refrigerator.

60 The invention also contemplates the use of

forms of elastic material which may be manually filled with water and placed in the freezing compartment to produce frozen bodies of ice of novel form. These ice molds may, for example, be composed of two hollow semi-spherical rubber cups, 5 much like the buckets of the conveyor means referred to above, which are filled under water and then brought into sealing engagement at their edges, the two halves being slightly compressed at portions remote from the inter-engaging edges 10 as they are filled. Upon release of pressure, it will be found that the two semi-spherical halves of the mold are held in sealing engagement with each other by the partial vacuum created by the release of pressure. These water-filled molds are 15 then placed in the freezing compartment. The expansion of ice during the freezing generally forces the two halves of the mold into their original non-pinched condition and the rubber mold section can then be readily separated from the 20 frozen ball of ice.

The invention will be further described with the aid of the accompanying drawings wherein several embodiments of the invention are illustrated by way of example. In said drawings,

25 Fig. 1 is a vertical section, partially in elevation, of an ice-forming mechanism constructed in accordance with the invention;

Fig. 2 is a similar section taken at right angles to the plane of Fig. 1 along the line 2—2 of the 30 latter;

Fig. 3 shows an enlarged detail illustrating the construction of the elastic cups forming part of the conveyor;

Fig. 4 shows a section of an ice mold adapted 35 to be manually filled with water and placed within the freezing compartment of a refrigerator;

Fig. 5 is a view of another embodiment of the invention, likewise in the form of an individual mold; while

40 Fig. 6 illustrates the mold of Fig. 5 filled with water and ready for placement within the refrigerator.

The apparatus shown in Figs. 1, 2 and 3 may be incorporated in any type of refrigerator, 45 whether electric or gas operated, the only important modification over the present constructions being in the arrangement of the expansion coils and in the absence of the customary ice cube trays. In accordance with the form of the invention illustrated in Figs. 1 to 3, the evaporator coils, which are shown diagrammatically at 10, are so disposed as to provide an interior freezing compartment 11 which is surrounded by such coils and is accordingly subjected to a low temperature, that is, a freezing temperature, during the normal operation of the refrigerator. The evaporator coils may be housed within a casing 12 which is supported in any suitable fashion within 50 the refrigerator.

Attached to the casing 12 is a tank 13 which is adapted to contain a body of water for use in the manner to be explained more fully hereinbelow. This tank is provided with a cover 14 having apertures 15, 16 and 17, and above such plate is positioned one or more sections of sheets 18 of rubber or other insulating material to the end that the water in the tank 13 is protected against the extreme cold in the compartment 11 and thus kept from freezing.

Two pairs of vertically aligned wheels or drums 19, 20 and 21, 22 are journaled within the compartment 11 and tank 13, the shafts 19a and 21a of the wheels 19 and 21, respectively, being supported upon brackets 23 and 24 depending from the inner upper wall 25 of the expansion coil casing, and upon trunnions 23a welded or otherwise secured to the inner wall of the casing 12 (Fig. 2); while shafts 20a and 22a of the wheels 20 and 22 are supported upon brackets 26 and 27, respectively, depending from the cover plate 14 of the tank 13. The wheels are in the form of hollow drums of sheet metal or other suitable material.

25 In the illustrated embodiment of the invention shown in Figs. 1 and 2, the wheel 22 is adapted to be rotated in step-by-step fashion by means of a lever 28 loosely pivoted upon the shaft 22a and having a handle 29 which can be engaged through the aperture 30 in the front wall 31 of the casing 12. The lever 28 is provided with a pawl 32 which cooperates with a ratchet wheel 33 fixed to the shaft 22a and likewise to the wheel 22, so that upon reciprocation of the lever 28, the wheel 22 is rotated intermittently in one direction. A gear 34 is fixed to the wheel 22 and meshes with a gear 35 attached to the wheel 20, the two gears being of equal diameter, so that an equal and opposite movement is transmitted to the wheel 20. 40 An endless belt is roved about each of the pairs of wheels 19, 20 and 21, 22, the belt consisting of a web 36 of rubber or other suitable flexible material within which are embedded or to which are attached horizontal rows of hollow, preferably 45 semi-spherical pockets or cups 37. When the web 36 and cups 37 are made of the same material, such as rubber, they may be fashioned or molded integrally, as will be clear from Fig. 3. The horizontal rows of cups are positioned at 50 equally spaced intervals upon the two belts 36 and the belts are so arranged with reference to each other that as they round the lower sprockets 20 and 22 the cup-shaped pockets 37 of the adjacent runs of the belts come into alignment and 55 engage each other at their outer circumferential edges, as is clearly shown in Figs. 1 and 3.

The wheels or drums 19 and 21 are provided with recesses 38 shaped to receive the spherical cups or pockets 37, while the lower wheels 20 and 22 are provided with recesses 39, which, while also adapted to receive the cups 37 are provided with raised bosses or knobs 40, for a purpose which will be described more fully hereinbelow.

In the operation of the mechanism so far described, oscillation of the lever 28 will cause equal and opposite rotation of the wheels 20 and 22 and thus also of the two endless belts 36. As each of the cups 37 enters the body of water in the tank 13, it gradually fills with water and 70 moves into a recess 39 of the corresponding wheels. During its subsequent movement the rubber cup 37 is pressed with greater and greater force against the bottom of the recess 39 and thus becomes depressed inwardly in the manner shown 75 at 41 in Fig. 3. This depression causes expulsion

of any bubbles of air that may have clung to the interior surface of the cup and at the same time places the bottom of the pocket under tension. As the opposite cups on the two belts move upwardly between the two wheels 20 and 22, as indicated at 42, they are brought into gradual engagement and by the time they reach a position on the line joining the axes of the shafts 20a and 22a, as shown at 43 in Fig. 1, the upper portion of their abutting edges have been brought into close engagement and upon an additional slight upward movement the lower edges are likewise brought into engagement. Thereafter the pressure of the bosses 40 against the central portions of the cups is released and the inter-engaged cups, now joined into substantially spherical molds, with depressed opposite "poles", tend to assume the completely spherical condition, but succeed in doing so only partially, there being created at the same time a relative vacuum 20 within the molds which enables the external atmospheric pressure to hold the two halves of each mold tightly in engagement with each other. The water-filled molds now travel upwardly or remain within the freezing compartment 11, and 25 due to the refrigerating action of the coils 12, the water gradually freezes.

The expansion caused by the freezing is taken up either by the expansion of the mold to the more nearly completely spherical conditions or by 30 separation of the two halves of the mold. This separation, however, will not cause any loss of the contents of the molds as the water is by that time in solid condition.

As the two-part molds reach a position shown 35 at 44 upon a line connecting the axes 19a and 21a they are forced apart as each conveyor run begins to round its own wheel. The almost spherical mass of ice will now be loosened from one or the other semi-spherical pocket and will move around 40 either the sprocket 19 or the sprocket 21.

Means are provided in accordance with the invention for ejecting the frozen ball of ice from the cups on the two belts. In the embodiment of the invention shown in Figs. 1 to 3, this ejector 45 means comprises hook members 45 and 46 loosely pivoted upon brackets 47 and 48, respectively, which depend from the inner wall 25 of the expansion coil casing. The relatively sharp free ends of the hook members are positioned so as 50 to engage the balls of ice, shown for example at 49, as they turn into the vertical outer runs of the respective conveyors. The ejected balls of ice are caught within troughs 50 and 51 which direct them into a common hopper 52 opening 55 toward the exterior of the casing 10. The front wall 31 of the casing 10 is provided with a door 53 which may be raised by means of a handle 54 to permit the discharged balls of ice to be removed, the door being held in lowered, closed 60 position by means of a spring detent 55.

The troughs 50 may be arranged so close to the conveyor belts that if a hook fails to eject a ball of ice, the latter will engage and be ejected by the inner edge of the adjacent trough.

As shown clearly in Fig. 2, each of the webs 36 is provided with four cups in each horizontal row. It will, of course, be obvious that any number of cups or pockets may be arranged in each row and a corresponding number of ejector hooks 70 45 will be provided.

If desired, a hood 56 may be provided over each of the wheels 19 and 21 in order to reduce evaporation of the ice balls as much as possible. The outer ends of these hoods may act as stops 75

limiting the inward movement of the hooks 45 and 46 as indicated at 51, to prevent damage to the webs or the edges 58 of the pockets 37.

The thickened outer edges 58 of the cups may 5 be provided with annular recesses of semi-circular cross-section, as shown at 58a, the recesses of opposite cups on the adjacent runs of the two belts being adapted to be brought into alignment as the cups move upwardly between the wheels 10 20 and 22. The latter are so positioned relatively to each other that they exert a slight pressure upon the thickened edges 58, thereby compressing the walls of the torus-like recess 58a formed by the fitting together of two opposite cups, 15 thereby expelling a part of the water. Upon release of the joined cups from the wheels 20 and 22 the walls of the torus-like recess will tend to expand to their normal condition and will thereby create a partial vacuum within such recess. 20 This vacuum may be sufficient to hold the two halves of the mold together and the depression of the outer ends of the two-cup mold may accordingly be dispensed with. I prefer, however, to utilize both the compression of the thickened 25 edges of the two cups and also the depression of the opposite ends of the two cups to create a sufficiently high vacuum to cause the two parts of the mold to cling to each other in water-tight relation as illustrated in Fig. 3.

30 It will, of course, be necessary to insure that the water in the tank 13 does not freeze. To this end it may be insulated against the cold in the compartment 11 in any suitable fashion as by means of the sheet 18 of rubber or similar 35 material. This insulation may be aided by making the apertures 15, 16 and 17, through which different runs of the two belts travel, as small as possible and the cover 18 of rubber or other insulating material may be made to overlap these 40 openings, as shown in Fig. 1, the rubber or other flexible sheet yielding as a pocket moves into or out of the tank 13. The coils 10 of the evaporator will be suitably disposed to prevent freezing of the water in tank 13.

45 If desired, certain of the coils 10 may be positioned within the space between the runs of each belt so as to produce a greater refrigerating effect upon the ice molds. The temperature of the water in the tank 13 should, however, be kept at 50 least several degrees above 32° F.

The edges of the sheet 18 overlying the aperture 16 may engage the emerging cups and thus exert a wiping action thereon to remove water clinging thereto.

55 Any suitable gauge device may be provided to indicate the level of the water in the tank 13. This level should always be maintained above the height of the shafts 20a and 22a. This gauge may take the form of a water charging spout 60 which extends forwardly of the front wall of the tank and communicates with the interior thereof, the bottom of such spout being approximately at the lowest permissible level of water in the tank. The absence of water in the spout 60 will indicate that the tank must be replenished.

The webs 36 will, of course, be wet as they emerge from the opening 16 and any water that does not run back into the tank 13 will become frozen within the space 11. There will not, however, be any accumulation of ice upon these webs because any ice crust thereon will be melted away when the webs reenter the tank 13.

Should a mold reach the position indicated at 44 before the water is frozen, no damage will result as the water will merely run down the belts

36 and will return to the tank 13 by way of the opening 16. If after several reciprocations of the lever 28 no ice balls appear at the hopper 52, it will be a signal to the householder either that the refrigerator is not operating properly or that 5 he is overtaxing the capacity of the freezing mechanism.

The present invention also contemplates the use of ice molds of the type shown in Figs. 1 to 3 for use individually in refrigerators of present 10 day construction. The mold consists of two halves 61 and 62 (Fig. 4) made of rubber or other suitable resilient material, the molds being preferably provided with thickened edges as shown at 63 to insure water-tight engagement. The molds 15 are filled under water, fitted together, and then depressed at their opposite ends as indicated at 64. Upon removal of the molds from the water and release of pressure thereon a partial vacuum 20 will be created within the molds to an extent 25 sufficient to hold the two halves together in water-tight relation. The molds can then be placed within the freezing compartment of the refrigerator and after freezing of the water the mold can be readily separated from the ball of 30 ice. In this way individual masses of ice of novel shape can readily be produced. It will be obvious that by providing suitable fillets within the mold, different shapes can be imparted to the frozen mass of ice.

Figs. 5 and 6 illustrate an individual mold constructed similarly to the cups pockets shown in Figs. 1 to 3, the mold consisting of two halves 65 and 66 which may be constructed and manipulated similarly to the molds shown in Fig. 4 except that the meeting edges are flanged, as shown at 67, and provided with annular recesses 68 of semicircular cross-section. By pinching the joined edges 67 and 68 while under water, enough water can be expelled to cause the partial vacuum 40 within the torus-like chamber formed by the two recesses 68 to hold the edges in water-tight relation. This vacuum may, however, be supplemented by a vacuum within the interior of the mold created by depressing, under water, the 45 opposite ends of the mold, as shown in Fig. 6.

It will be understood that various changes in the size and relationship of parts may be made in the forms of the invention illustrated within the scope of the appended claims without departing from the spirit of the invention. Thus, while the conveyor mechanism has been described as being manually operated, it will be obvious that it may be operated also by means of an electric motor to which it may be coupled by way of a 55 reduction gearing. Also fewer or more than four cups may be arranged in each horizontal row on the belts 36, and the latter need not be in the form of continuous webs, but may be replaced by chains. The handle 29 may extend through the 60 opening 30 and may, in fact, together with the hopper 52, extend to the outside of the refrigerator, or else the rockshaft to which the handle is attached may extend to the exterior of the refrigerator and the handle be fixed to the free end 65 thereof, so that the handle may be operated without opening the refrigerator door.

I claim:

1. The combination with a refrigerator, of mechanism for carrying individual masses 70 of water, into the freezing zone of the refrigerator, comprising two endless conveyors adapted to travel in opposite directions with two of their runs in proximity, driving mechanism for said conveyors, cups of resilient material ar- 75

ranged in horizontal alignment on the two conveyors, a water tank within which the lower portions of said conveyors travel and within which the cups become filled, and means for effecting water-tight engagement between the aligned cups.

2. The combination with a refrigerator, of mechanism for carrying individual masses of water, into the freezing zone of the refrigerator, 10 comprising two endless conveyors adapted to travel in opposite directions with two of their runs in proximity, driving mechanism for said conveyors, cups of resilient material arranged in horizontal alignment on the two conveyors, a 15 water tank within which the lower portions of said conveyors travel and within which the cups become filled, and means for partially compressing said cups as they are brought into alignment within said tank to create a partial vacuum 20 within the space confined by the joined cups to cause such cups to be held in water-tight engagement by the pressure of the external atmosphere.

3. The combination as set forth in claim 2, including hook members arranged adjacent to 25 the path of the conveyors so as to engage the frozen masses of ice and eject them from the cups.

4. The combination as set forth in claim 2, including mechanism for discharging the frozen 30 masses of ice from the conveyors.

5. The combination as set forth in claim 2 including ejector mechanism arranged adjacent to the path of the conveyors for discharging the frozen masses of ice therefrom, a chute for receiving the ejected ice masses, and a hopper at 35 the end of the chute for collecting said masses.

6. The combination as set forth in claim 2 wherein the cups are made of rubber and have thickened upper edges along which the cups on 40 the conveyors engage each other.

7. The combination as set forth in claim 2 wherein the cups are made of rubber and have thickened upper edges along which the cups on the conveyors engage each other, said thickened 45 edges being provided with semi-annular recesses, the recesses of two joined cups forming a torus-like chamber which is adapted to be compressed as the cups are brought into alignment.

8. The combination as set forth in claim 1 50 wherein the conveyors are composed of webs of rubber and wherein the cups are likewise of rubber and are connected to said webs.

9. The combination as set forth in claim 2 wherein said driving mechanism comprises a 55 ratchet wheel associated with one of the conveyors, a reciprocating lever and pawl mechanism for intermittently rotating such ratchet wheel, and gearing connecting the two conveyors to cause them to travel in opposite directions.

60 10. A mold for use in freezing individual masses of water in a household refrigerator comprising two hollow, substantially semi-spherical mold sections made of resilient material, said mold sections adapted to be joined together under water 65 with their edges in engagement and to be depressed at their opposite ends to create a partial vacuum in the interior thereof which causes the external atmosphere to hold the two halves in water-tight relation.

70 11. The combination with a refrigerator, of apparatus for freezing masses of water in the refrigerator, comprising a plurality of molds each consisting of two hollow substantially semi-spherical sections made of resilient material, said

mold sections adapted to be joined together under water with their edges in engagement and to be depressed at their opposite ends to create a partial vacuum in the interior thereof which causes the external atmosphere to hold the two halves in 5 water-tight relation.

12. A mold for use in freezing individual masses of water in a refrigerator, comprising two hollow substantially semi-spherical sections of resilient material, the edges of said sections being thickened and provided with an annular recess, the recesses of the two sections being adapted to be brought into alignment as the sections are fitted against each other to produce a torus-like chamber, said thickened ends being adapted to be 15 pinched as the mold is filled under water and the sections thereof brought into engagement, whereupon on removal of the mold from the water and release of the edges thereof, a partial vacuum is created in said torus-like chamber which enables 20 the external atmosphere to hold the sections of the mold in water-tight connection.

13. In a refrigerator, an endless conveyor mechanism having cups thereon for conveying individual masses of water within the freezing 25 zone of the refrigerator, a water supply tank through which the conveyor is movable for refilling the cups, a layer of insulating material for protecting the contents of the tank against freezing and extending between the runs of the conveyor, and a device for ejecting the frozen masses 30 of ice from said cups.

14. In a refrigerator, an endless conveyor supported adjacent to the refrigerating coils of the refrigerator, cups on said conveyor for holding 35 individual masses of water and exposing them to the freezing effect of said refrigerating coils, mechanism for operating said conveyor, a water supply tank through which the conveyor is movable for refilling the cups, and a layer of insulating material covering the tank for protecting the contents of the tank against freezing, said insulating layer extending between the runs of the conveyor and being apertured to provide passage 40 for the cups therethrough.

15. The combination with a refrigerator and the cooling coil thereof, of conveyor mechanism for carrying individual masses of water within the freezing zone of the cooling coil, said conveyor being provided with receptacles for receiving said 50 masses of water, means for driving said conveyor, ejecting mechanism for releasing the frozen masses of ice from the conveyor receptacles, and comprising a member engaging the frozen masses from below as said masses travel toward said 55 member, and a chute for receiving the ejected masses of ice.

16. In a refrigerator, a pair of endless conveyors adapted to travel in opposite directions with two of their runs in proximity, the upper portions of 60 the conveyors traveling through the freezing zone of the refrigerator, driving mechanism for said conveyors, cups of resilient material arranged in horizontal alignment on the two conveyors, a water tank within which the lower portions of 65 said conveyors travel and within which the cups become filled, and hook members adjacent to the inoperative runs of the conveyors and acting to engage the frozen masses of ice from beneath to 70 eject them from the cups, a chute associated with each hook member for receiving the ejected masses of ice, and a common hopper into which said chutes lead.

BALTHAZAR H. THEO. MULCH.
